UNITED STATES PATENT OFFICE.

ALBERT TURNER, OF WORCESTER, MASSACHUSETTS, ASSIGNOR TO NORTON COMPANY, OF WORCESTER, MASSACHUSETTS, A CORPORATION OF MASSACHUSETTS.

STEADY-REST SHOE.

Application filed April 5, 1921. Serial No. 458,705.

To all whom it may concern:

Be it known that I, ALBERT TURNER, a citizen of the United States of America, residing at Worcester, in the county of Worcester and State of Massachusetts, have invented certain new and useful Improvements in Steady-Rest Shoes, of which the following is a full, clear, and exact specification.

My invention relates to work supports and more particularly to a steady rest shoe for metal reducing machines, such as cylindrical grinding machines.

In some classes of cylindrical grinding where work of a given size is produced in large numbers, the work shoe of the steady rest is, in some cases, formed with a cylindrical bearing surface adapted to fit the surface of the work when ground to the required size. Such a construction, however, leaves edges where the cylindrical surface ends, upon which the work rests at the beginning and during the major part of the grinding operation, because it is then of slightly greater diameter than the curvature of the shoe. Since the work is supported on these edges by narrow line contacts, under the grinding pressure, they tend to dig into the work and mar its surface, particularly in roughing operations when the pressure on the work is relatively great due to a heavy cut being taken. If such edges of a shoe are rounded off to prevent digging into the work, the construction is still objectionable in that it presents external cylindrical surfaces instead of plane or concave surfaces, to support the work, and it has been found particularly in centerless grinding machines that the work cannot be satisfactorily steadied by such a surface.

It is the object of my invention, therefore, to overcome these difficulties by providing a shoe having a bearing surface which will fit the work when ground to size and also support it at all times during the grinding operation on a plane or concave surface or surfaces, whereby scratching or otherwise marring its surface is substantially eliminated and the work is steadily held up to the action of the grinding wheel during the initial as well as the final phases of the operation.

In the accompanying drawings forming a part of this specification and in which like reference characters refer to like parts:

Figure 1 is a side elevation of my im-

proved steady rest shoe applied to a steady rest of known construction, and showing the relation between the grinding wheel, work and shoe at the completion of a grinding operation; and

Fig. 2 is a similar view showing a slightly modified form of shoe and the relative positions of wheel, work and shoe at the beginning of a grinding operation, the size of the work being exaggerated to clearly illustrate the invention.

In the practice of my invention, I provide a work shoe 1 having a bearing surface or surfaces to receive the work W rotating in the direction indicated by the arrows (Figs. 1 and 2) on the usual centers and in operative engagement with the rotating grinding wheel V. Any suitable material, such as hardened steel, may be used to form that part of the shoe forming the bearing surface or surfaces. I may, and preferably do, make the shoe readily detachable from the usual adjustable support 3, which is movably mounted on the base member 4, and adjusted horizontally and vertically to bring the shoe into proper supporting relation to the work by the screws 5 and 6 respectively. The base of the steady rest is clamped to the table 7 by the usual clamping means 8. The means for supporting and adjusting the position of the shoe here described and shown more or less diagrammatically in the drawings are substantially the same as those shown in the patent to Wilcox et al No. 1,214,629 dated Feb. 6, 1917, to which reference is made for a full disclosure of these parts. The manner of connecting it to the steady rest is similar to that shown in the patent to Norton No. 1,009,989, Nov. 28, 1911, the shoe being shewn provided with a three point support and being clamped in place by the screw 9. The shoe is shown having this general form and in connection with these specific structures merely for illustrative purposes, for it is obvious that it could take other forms to adapt it for use with other types of steady rests, the invention residing more particularly in the arrangement of the bearing surfaces for supporting the work from the beginning to the completion of the grinding operation.

In the specific embodiment of my invention selected for illustration, I have shown the shoe 1 having a cylindrical bearing surface or surfaces 11 adapted to fit the work W.

at the finish of the grinding operation (Fig. 1) so that the work bears upon the cylindrical surface throughout. In Fig. 1, I have shown a form of shoe in which this cylindrical surface is broken intermediate its outer edges by a cut-out portion 12 so as to form in effect two cylindrical surfaces having equal radii, and being parts of the same surface of revolution. This type of shoe is well adapted for use in taking light finishing cuts. In Fig. 2, I have shown a shoe having a cylindrical bearing surface unbroken between its opposite edges, and this type of surface is better adapted for use in taking heavy roughing cuts than the type shown in Fig. 1, for the reason that in taking heavy cuts the abrasive grains in the wheel are worn away rapidly and large chips are removed, some of which may lodge in the cutout portion 12 and finally get caught between the work and the bearing surface of the shoe and thus produce scratches on the work. With the shoe having the continuous cylindrical bearing shown in Fig. 2 such a contingency is less liable to arise.

In both forms of shoes illustrated it is obvious that, since the work to be ground fits the cylindrical bearing surface of the shoe at the finish of the grinding operation, it would be supported at the beginning of the grinding operation only at the outer edge or edges of said surface if no further provision were made. Hence I have continued the cylindrical bearing surface 11 with auxiliary bearing surfaces 13 and 14 forming, in effect, extensions of the cylindrical surface and which are shown in the drawings as being substantially tangent to the cylindrical surface and merge thereinto. The outer edges 15 and 16 of said shoe are thereby spaced apart a distance sufficient to receive the work therebetween.

In Fig. 2 the size of the work is shown exaggerated compared with the finished size in Fig. 1 to more clearly illustrate the manner of support of the work at the beginning of the grinding operation, it being understood that the amount of stock to be removed is ordinarily a very small fraction of an inch on the diameter of the work.

As the grinding proceeds the shoe is of course moved relatively to the work by adjusting the screws 5 and 6, so that the work is lowered into the shoe until it finally fits the cylindrical bearing surfaces thereof at the finish of the grinding operation. It will therefore be seen that I have provided a construction which will support the over sized work on plane surfaces arranged at an angle to each other to form a V-shaped rest. These plane surfaces merge tangentially into a concave partial cylindrical surface which has its radius substantially equal to that of the finished work for which the shoe is adapted. Hence as the work becomes smaller it gradually settles down in the rest until it finally touches the cylindrical surface and is then supported along its entire extent. Since the work is at no time supported on an external cylindrical surface and there is no abrupt change from such a surface to a concave one, the work is permitted to move down the supporting plane surfaces of the V-rest gradually and without abrupt change. The outer tangential surfaces act substantially as portions of the concave cylindrical surface and the radius of the work intersecting the supporting surface remains normal and perpendicular to such support at all times.

Having thus described my invention, what I claim as new and desire to secure by Letters Patent is:

A grinding machine steady rest comprising a steady rest shoe of wear resisting material having a concave partial cylindrical surface of revolution whose radius substantially equals that of the finished work for which the shoe is adapted, said cylindrical surface merging tangentially into two plane surfaces arranged at an angle to form a V-shaped work rest, whereby work will be constantly supported on a plane surface during the initial stages of grinding until it substantially fits the partial cylindrical surface and is there supported fully for the final operation.

Signed at Worcester, Massachusetts, this 4th day of April 1921.

ALBERT TURNER.
